[57] CLAIM

The ornamental design for fuel nozzle ad display board, as shown and described.

DESCRIPTION

FIG. 1 is a perspective view of a fuel nozzle and display board showing my new design;

FIG. 2 is a top plan view thereof;

FIG. 3 is a bottom plan view thereof;

FIG. 4 is a left side elevational view thereof;

FIG. 5 is a front elevational view with the straps connected;

FIG. 6 is a left side elevational view with the straps connected.

The broken line disclosure of a portion of a fuel nozzle in FIG. 6 is for illustrative purposes only and forms no part of the claimed design.

FIG. 5

FIG. 3
